INTEGRAL COWL AND GRAB BAR FOR A TRACTOR

Arvid Harlan Saele and Michael Pier Hutton, Iowa, Iowa,
assignors to Deere & Company, Moline, Ill.

Filed May 16, 1974, Ser. No. 470,377

Term of patent 14 years

Int. Cl. D12—09

U.S. Cl. D40—5

FIG. 1

FIG. 2

FIG.3

FIG.4

FIG. 1 is a front elevational view of our design for an integral cowl and grab bar for a tractor.

FIG. 2 is a right side elevational view thereof, the left side being a mirror image of the right side shown herein.

FIG. 3 is a rear perspective view thereof.

FIG. 4 is a top plan view thereof.

We claim:

The ornamental design for an integral cowl and grab bar for a tractor, substantially as shown.
